SNOW PLOW

Robert E. Stevenson, Indianapolis, Ind.

Application January 6, 1937, Serial No. 119,292

3 Claims. (Cl. 37—53)

This invention relates to the art of plows and particularly to a snow plow, the primary object of which is to throw the snow aside by simply pushing the plow along without having to pick up the snow a shovelful at a time and throw it aside. A further important advantage of my invention lies in the fact that it may be made at a comparatively low cost and is light in weight so that it may be operated without undue fatigue. A still further advantage of my invention is that it may be easily operated over rough walks and the like.

These and other objects and advantages will become apparent to those versed in the art from the following description of one particular embodiment of my invention as illustrated in the accompanying drawing, in which

Fig. 1, a perspective view of a preferred form of my plow;

Fig. 2, an elevation of the side next to the operator; and

Fig. 3, a top plan view.

Like characters of reference indicate like parts throughout the several views in the drawing.

I form the plow share 9' from sheet metal of the desired thickness to have a forward scraping or cutting edge 11'. From this edge 11', the metal is carried rearwardly and around upwardly to form in effect a mold board 10'. The metal is carried back from the edge 11' to form a flat or plane portion having a rearwardly extending length a' on the one side, here shown as the right hand side, greater than the length b' on the opposite side and the curved portion extending rearwardly and upwardly and around forwardly therefrom forms the part 10' which will collect and guide the snow to one side of the plow.

A very important feature of the invention is that the forward edge 11' is at right angles to the line of travel of the plow as it may be pushed along over the surface being cleaned. In other words the edge 11' is at right angles to the handle 12 which is secured to the plow by means of any suitable bracket 13 attached to the plow on its rear side substantially at the junction of the upwardly curving portion with the forward plane portion. I have discovered that contrary to the usual practice in plowing operations, the plow is most effective by having this forward edge 11' formed at right angles to the handle 12 rather than being sloped to one side. In fact it has been my experience that sloping the forward cutting edge gives very unsatisfactory performance and causes the plow to slip sidewise and not maintain a forward course.

Another feature of my invention resides in the fact that I provide means for permitting the plow to be pushed along over obstructions by rocking the handle 12 downwardly without having to lift the plow.

In the form of my invention shown in Figs. 1-3, inclusive, the upwardly extended rear portion 10' is extended by suitable curves to the cutting edge 11' at the narrow end b' to keep the snow from escaping at that end and, aided by the curves, to cause the snow to roll and slide toward the opposite wide, discharge end a', and to increase the clearance and facilitate the discharge of the snow from the plow, I curve the rear portion 10' rearwardly and also curve the adjacent lower or plane surface downwardly for the same reason.

To give the cutting edge 11' a better contact or bite against the surface of the side-walk, I form a depending flange or runner 18 at the end a', gradually increasing in width from nothing at the edge 11' to approximately an inch near where the curve for the rear upwardly extended portion 10' begins, and there this runner merges into the adjacent curve of the plane. The flange 18 thus gives the proper tilt of the plane to cause the edge 11' to bite and does not obstruct the discharge of snow.

By forming the plow to have a forward cutting edge at right angles to the direction of travel of the implement and having a mold board across the rear of the plow in a sloping position in reference to the line of travel, I have provided an unusually efficient tool for shifting to one side materials from an area to be cleaned by simply pushing the plow straight ahead. The peculiar formation of the plow eliminates any tendency of it to be shifted sidewise as the snow or the material is being carried laterally of the plow under the forward movement thereof. Where the snow is frozen or tramped, a short backward and forward movement will usually serve to loosen it for easy removal by the plow.

While I have herein shown and described my invention in the one form as now best known to me, it is obvious that structural variations may be made without departing from the spirit of the invention and I therefore do not desire to be limited to this precise form beyond the limitations as may be imposed by the following claims.

I claim:

1. A plow formed to have a forward scraping edge from which the plow extends rearwardly into an upwardly curved portion which is angularly disposed in relation to said edge, and fur-

ther formed to have a runner on which the plow may fulcrum to lift said edge, said runner comprising a forwardly tapering member extending from the cutting edge toward the discharge end 5 of the plow.

2. A plow formed to have a forward scraping edge from which the plow extends rearwardly into an upwardly curved portion which is angularly disposed in relation to said edge, and 10 formed to have a plane portion between said edge and said curved portion and further having the end of the angularly disposed portion nearest the scraping edge curved to direct the snow toward the other end which is the discharge end 15 of the plow and having the discharge end formed with a tapered flange which extends downwardly and widens rearwardly from the cutting edge

along the plane portion of the plow and then flares outwardly at the curved portion to increase the area of discharge.

3. A plow formed to have a forward scraping edge from which the plow extends rearwardly to 5 a flanged portion and formed to have a plane portion between said edge and said flanged portion and further having the end of the flanged portion nearest the scraping edge flanged upwardly across the plane to prevent escape of snow at 10 that end of the plow and curved to direct the snow toward the other end which is the discharge end of the plow, said discharge end being flared outwardly to increase the area of discharge and flanged downwardly into a runner tapering to 15 the forward scraping edge.

ROBERT E. STEVENSON.
